UNITED STATES PATENT OFFICE

PAUL VIGNOS, OF CANTON, OHIO, ASSIGNOR, BY MESNE ASSIGNMENTS, TO REPUBLIC STEEL CORPORATION, OF YOUNGSTOWN, OHIO, A CORPORATION OF NEW JERSEY

LOCKING MECHANISM

Application filed October 18, 1928. Serial No. 313,253.

This invention has for its object the provision of a locking mechanism for a locker or other closure, which will be simple in operation, of sturdy construction, permit of easy 5 assembly, and present withal a neat appearance.

Lockers, of the type commonly used in schools, gymnasiums, etc., as furnished by locker manufacturers, are usually equipped 10 with individual cabinet locks, which are so made, that all of the locks in each group of six lockers, may be opened by means of a master key, the master key being retained by the building superintendent or other custo- 15 dian, to enable the latter to inspect the contents of the lockers when he so desires. As a matter of expedience, each locker is also equipped by the manufacturer with a padlock attachment, in order that the locker may be 20 furnished with either a padlock or a cabinet lock, at the option of the purchaser.

Assuming that a school building is equipped with 1500 lockers, this being the average number of lockers in a typical high 25 school building, it would be necessary, where the lockers are equipped with cabinet locks only, for the superintendent to carry, or have available for ready use, 250 master keys for the cabinet locks.

30 If the lockers were supplied with padlocks only, the superintendent would be obliged to carry 1500 keys, or one key for each padlock. Too often, students, having lost their padlock keys, purchase and install other padlocks 35 on the lockers, and neglect to furnish the superintendent with duplicates of such new padlock keys. The difficulties which arise, when the superintendent wishes to inspect the contents of a locker thus furnished with 40 a new padlock, are obvious.

Even when cabinet locks are installed on each locker, students often take advantage of the padlock attachment on the locker to lock their own locker by means of a padlock. 45 As a result, when the superintendent desires to inspect the locker contents, he is forced to lose much valuable time in opening lockers which are thus doubly locked, and particularly if the student has failed to supply him 50 with a duplicate key for such padlock.

In the highly improbable event that all of the students have supplied the superintendent with duplicates of the padlock keys, the difficulties would still be great, as he would be forced to carry, or have available for ready use, a key for each padlock, or 1500 keys, in addition to the 250 master keys for the cabinet locks. The mere possession and use of so great a number of keys inevitably results in confusion, as will be readily apparent to any- 55 one who has had occasion to carry many keys.

It is a primary object of the present invention to provide a locking mechanism for a locker or other closure, which mechanism includes a cabinet lock and a padlock, either 60 of which, when operated singly, will serve to unlock the locker.

Another object of the invention is to provide a locking mechanism for a locker or other closure, which includes a cabinet lock 70 and a padlock, the padlock being capable of being opened by means of a key which is retained solely by each student, and the cabinet lock being capable of being opened by means of one master key which opens all of the cabinet locks in the school building, and which is retained solely by the superintendent. 75

Other objects of the invention will become more readily apparent in the course of the following description of one embodiment of 80 the invention, taken in connection with the accompanying drawings wherein:

Fig. 1 is a front elevation of a locker in which is employed the novel features of the present invention; 85

Fig. 2 is an enlarged fragmentary cross-section through the locker door, taken on the line 2-2 of Fig. 1, and showing the various parts of the locking mechanism, the cabinet lock being omitted for clearness of illustration; 90

Fig. 3 is an enlarged fragmentary cross-section through the locker, taken on the line 3-3 of Figs. 1 and 4;

Fig. 4 is an enlarged fragmentary front elevation of the locker, showing all the parts of the locking mechanism in relative position; 95

Fig. 5 is a fragmentary cross-section through the locker door, taken on the line 100

5—5 or Figs. 1 and 4, and showing the latching mechanism and method of securing the handle to the latching bar;

Fig. 6 is a perspective view of the handle;

Fig. 7 is a fragmentary view of the rear of the locker door, showing the manner in which the latching bar housing is cut away to provide space for mounting the locking mechanism on the door;

Fig. 8 is a perspective view of the padlock clip;

Fig. 9 is a perspective view of the cabinet-lock plate, and

Fig. 10 is a view of the shoulder rivet employed in securing the padlock clip to the cabinet-lock plate.

Referring more particularly to the drawings wherein like reference characters designate like parts, the locker includes a sheet-metal door frame 1, and a door 2 hinged thereon. The door 2 is formed at one of its side edges with a tubular reinforcement 3, which also serves as a housing for a latching bar 4. The latching bar 4 is forced into latching position by means of keepers 5, which are mounted at vertically spaced points on the frame 1. The construction and operation of the latching mechanism is fully described in the patent to Sturm and Caldwell, No. 1,671,328.

The door 2 is provided with spaced slots 6, and the latching bar 4 is provided with spaced slots 7, the slots 6 and 7 being in registration with each other when it is desired to attach a handle 8 to the latching bar. In attaching the handle 8 to the latching bar 4, the tenons 9 of the handle are inserted through the slots 6 and 7, the upper tenon forcing the flat spring 10, which is secured at its lower end to the latching bar, back to the position indicated in dotted lines in Fig. 5. The latching bar is then permitted to move relatively to the handle, and the spring assumes the position shown in solid lines in Fig. 5, and thus prevents accidental detachment of the handle from the latching bar, as well as relative movement between the handle and the latching bar.

The handle 8 is further provided at its lower end, with a U-shaped portion 11, each leg of which is provided with a centrally disposed hole 12, these holes being in registration with each other.

The tubular reinforcement 3 is cut away, as at 13 (see Fig. 7), and a slot 14 is provided in the door adjacent the reinforcement at this point, and extending in line with the U-shaped portion 11 of the handle 8, this slot serving a purpose to be presently described. A hole 15 is also provided in the door for receiving the barrel 16 of a cabinet-lock 17, provided with the usual bolt 18.

A cabinet-lock plate 19, provided with a centrally disposed hole 20, is formed with a flange 21 having a slot 22 and holes 23 therein.

A padlock clip 24 is formed with a flat rectangular portion 25 having slots 26 and 27 therein, and an offset tongue 28 having a hole 29 therein.

The padlock clip 24 is slidably secured to the outer face of the flange 21 of the plate 19, as by means of shoulder rivets 30, the rivets passing through slots 27 and holes 23 of the padlock clip and plate respectively, and the slots 26 and 22 being in registration with each other.

The locking mechanism is assembled on the door as follows:

Tongue 28 of the padlock clip 24 is inserted through the slot 14 in the door 2 and the plate 19 is secured as by welding to the rear face of the door in such position that the hole 20 therein registers with the hole 15 in the door, and the hole 29 of the tongue 28 registers with the holes 12 in the U-shaped portion 11 of the handle 8, as shown in Fig. 2. The cabinet-lock 17 is then secured to the plate 19 as by means of bolts 31 and nuts 32. A padlock 33 provided with a shackle 34 completes the locking mechanism.

The operation of the locking mechanism is briefly as follows:

The locker is latched and the locking mechanism locked in the usual manner by causing the bolt 18 of the cabinet-lock 17 to pass through the slots 22 and 26 in the plate 19 and padlock clip 24 respectively, the key for the cabinet lock being retained by the superintendent. The locking is completed by passing the shackle 34 of the padlock 33 through the holes 12 and 29 of the handle 8 and padlock clip 24 respectively, and locking the padlock. The key for the padlock is retained by the student.

Assuming first that the student desires to open the locker, he unlocks and removes the padlock 33, and then lifts the handle 8 to cause the latching bar 4, which is secured thereto, to become disengaged from keepers 5.

Assuming that the superintendent wishes to make an inspection of the contents of the locker, he unlocks the cabinet-lock 17, thereby retracting the bolt 18 from the slots 22 and 26 of the plate 19 and padlock clip 24 respectively. He then lifts the handle 8, causing the padlock shackle 34 to lift the padlock clip 24 a sufficient distance to cause the latching bar 4 to become disengaged from keepers 5.

The slot 14 in door 2 is of such length that when the door is closed and the padlock clip 33 is in place, as shown in Figs. 2, 3 and 4, the lower edge of tongue 28 will lie upon the lower edge of slot 14, and the upper edge of the slot 14 is located a sufficient distance above the upper edge of tongue 28 to permit the padlock clip 24 to slide upwardly on rivets 30 a distance limited by the length of slots 27.

It is apparent that either the superintendent or the student has access to the interior of the locker at all times and that it is unnec-

essary for the superintendent to have a key for the padlock, or for the student to have a key for the cabinet lock.

Furthermore, since the students are not supplied with keys for the cabinet locks, identical cabinet locks, all opened by the same key, may be installed on all of the lockers in the building. It follows therefore that it is necessary for the superintendent to carry only one key, and the confusion attendant upon the use of a multiplicity of keys is entirely obviated.

It will be readily understood that the locking mechanism shown and described is not intended to be limited for use with the particular latching mechanism herein described, but may be used in connection with various other types of latches.

It will also be understood that various changes may be made in the locking mechanism, per se, without departing from the invention, the scope of which is intended to be limited only by the appended claims.

Claims:

25 1. In combination with a door, a cabinet-lock plate secured to the rear face of the door and a padlock clip slidably secured to said plate.

30 2. A structure as defined in claim 1, in which the padlock clip is provided with a tongue which extends through the door and is adapted to be engaged by a padlock shackle.

35 3. In combination with a door, a cabinet-lock plate secured to the rear face of the door and having a slotted portion extending at right angles thereto, and a slotted padlock clip slidably secured to said portion.

40 4. A structure as defined in claim 3, in which the padlock clip is provided with a tongue which extends through the door and is adapted to be engaged by a padlock shackle.

45 5. Locking mechanism for a locker door or the like including a cabinet-lock plate secured to the rear face of the door and having a slotted portion extending at right angles thereto, a slotted padlock clip slidably secured to said portion and a cabinet lock secured to said plate and provided with

50 30 a bolt, which is adapted to enter the slots in the plate and clip.

55 6. A structure as defined in claim 5, in which the padlock clip is provided with a tongue which extends through the door and is adapted to be engaged by a padlock shackle.

60 7. A front for lockers and the like, comprising a door, a door frame, co-operating latching members secured respectively to said door and said frame, a fixed plate upon said door, a slidable clip mounted on said fixed plate, and separate means for locking said slidable clip to one of said latching members and to the fixed plate, said locking means being separately operable to unlock said door.

65 8. A structure as defined in claim 7, in

which the fixed plate is mounted on the rear face of the door and has a slotted portion extending at right angles thereto.

9. A structure as defined in claim 7, in which the slidable clip is provided with a tongue which extends through the door and is adapted to be engaged by one of said locking means.

10. A structure as defined in claim 7, in which one of said locking means is mounted on said fixed plate.

11. A front for lockers and the like, comprising a door, a door frame, a slidable latching bar in said door, a handle fixedly secured to said bar, keepers on said frame adapted to cooperate with said bar to latch the door closed, a fixed plate upon said door, a slidable clip mounted on said fixed plate, and separate means for locking said slidable clip to said handle and to the fixed plate, said locking means being separately operable to unlock said door.

12. A structure as defined in claim 11, in which the fixed plate is mounted on the rear face of the door and has a slotted portion extending at right angles thereto.

13. A structure as defined in claim 11, in which the slidable clip is provided with a tongue which extends through the door and is adapted to be engaged by one of said locking means.

14. A structure as defined in claim 11, in which one of said locking means is mounted on said fixed plate.

In testimony whereof I affix my signature.
